FACE AND HEAD PROTECTIVE DEVICE

Charles Evans Bowers, Chester, Pa.

Application November 15, 1938, Serial No. 240,442

4 Claims. (Cl. 2-8)

This invention has to do with protective devices of the type worn on the head of a person for protecting the face, eyes, and/or the head from injury incident to welding, grinding or other dangerous industrial operations.

Protective devices of this type include, as a characteristic element, a headband which fits on the wearer's head and carries the shielding part itself.

10 Accordingly the invention has in view, as a highly important object, the provision of a protective device of the character above noted which includes a headband comprising two parts which are pivotally joined together whereby the headband is adapted to snugly fit the head of the wearer. Another object is the provision of such a two part headband provided with means by which it may be rendered adjustable as to head encompassing extent to insure accurate and snug fitting on the wearer's head.

20 More in detail the invention contemplates a two part headband of the character above noted, and one part of which includes means to render the headband adjustable as to its extent whereby the peripheral size of the headband as an entirety may be adjusted.

25 Bearing in mind the dangerous conditions to which the wearer is subjected for long periods of time it is easily seen that the headband which carries the protective device should be positioned on the wearer's head in a secure, accurate and comfortable manner. The accomplishment of this desired result is of utmost importance and a foremost object of this invention.

30 In many fields of industrial work it becomes important to protect the upper portion of the face of a worker, and particularly the eyes, from conditions attending the work being done, say for instance the sparks coming from welding operations carried out in assembly work. Accordingly, this invention has in view, as an important objective, the provision of a protective device including a transparent shield curved to conform to the shape of a wearer's head and adapted to cover the upper portion of the face of a wearer, together with means for mounting the same on the wearer's head.

35 More in detail the invention has in view, as an object, the provision of the shield for the upper portion of a worker's face which is made from a flexible, transparent material having desired protective and noninflammable qualities which may be readily bent into a required curved formation. Associated with this material are means 40 for imparting to the same rigidly to maintain

its curved shape and perform its required shielding functions.

A particular object of the invention is the provision, in a protective device of the character above noted, of a transparent shield made from 5 a flexible material the edges of which are lined with a metallic framework to impart rigidity thereto.

Under conditions of actual usage it is not necessary that the shield be in effective position in 10 front of the upper portion of a worker's face at all times, there being many prolonged intervals in which its use is not required. The invention, therefore, has in view, as a further objective, the provision of a protective device of the character 15 above noted which includes means for mounting the same on the head of a wearer and to which means the shield is pivotally attached. With the shield so pivotally mounted it may be readily swung up into an out-of-the-way position above 20 the head of a wearer.

More in detail this invention contemplates an arrangement wherein the means for mounting the shield on the wearer's head takes the form 25 of a headband and to which headband the shield is pivotally attached.

Another more detailed object of the invention is the provision, in a device of the character above noted, of frictional devices associated with the pivotal mounting of the shield whereby the 30 latter maintains any adjusted position.

In pivotally mounting the shield on the headband a curved strip is preferably pivotally secured at each end to the headband, and the shield, together with its rigidifying framework, depends 35 from this strip. An important object of the invention is to provide for a detachable connection between the shield and the pivotally mounted strip which provides for the ready replacement of the shield element as occasion demands. 40

Yet another important object of the invention is the provision, in a protective device of the character above noted, of a two part headband the parts of which are pivotally joined together, and the front part of which carries means adapted 45 to cover the front portion of a wearer's head. This covering means not only serves in the positioning and fitting of the device, but also provides protective effects for that portion of the wearer's head which it covers.

To the end of insuring of good protective effects on the part of the covering for the front portion of a worker's head the invention has as an object the provision, on the front headband part, of means for spacing the same slightly 50.

from the wearer's head. Such means may take the form of a flexible sweatband that lines the front part of the headband. With this sweatband providing a slightly spaced relationship, and with the covering formed of a rigid material, good protective effects are provided.

Yet another important object of the invention is the provision, in a protective device of the character above described, of a two part headband the parts of which are pivotally secured together, together with a shield which is pivotally mounted on the same pivot points which secure the headband parts together.

Various other more detailed objects and advantages such as arise in carrying out the above noted thoughts in a practical embodiment will in part become apparent, and in part be hereinafter stated, as the description of the invention proceeds.

The invention, therefore, comprises a protective device which includes a two part headband the parts of which are pivotally attached together, with the rear part adjustable as to its extent, while the front part carries a head covering together with means for spacing the same from the wearer's head. Pivotally secured to the headband, preferably on the same pivot pins with the two parts thereof, is a strip which detachably carries a protective shield which is made from a transparent, flexible material that is curved to a required formation and provided with metallic framework on its peripheral edges.

For a full and more complete understanding of the invention reference may be had to the following description and accompanying drawing, wherein:

Figure 1 is a side view, with parts broken away, of a face and head protector made in accordance with this invention and illustrated as applied to the head of a wearer.

Figure 2 is a top plan view of the protector.

Figure 3 is an enlarged detailed view developing the mode of detachably securing the shield to the pivotally mounted strip.

Figure 4 is an enlarged detailed section through one of the pivotal assembly points of the shield and headband parts, and

Figure 5 is a detailed sectional view bringing out the construction of the adjustment in the rear headband part.

Referring now to the drawing, wherein like reference characters denote corresponding parts, the protective device of this invention is illustrated as including a two part headband made up of a front part referred to in its entirety as 10, and a rear part identified as 11. The front headband part 10 is preferably made from a material having required properties of rigidity and which may be suitably shaped while in a plastic state, there being certain fibrous materials now well-known and having the required properties.

Integrally formed with the front headband part 10 is a head covering, designated 12, which is designed to cover the upper portion of the front part of a worker's head. The lower edge of the front part 10 carries a sweatband 13 which may take the form of a leather sweatband that is bent over the bottom edge of the part 10 and detachably secured thereto as by the detachable fastening elements (snap fasteners) shown at 14. It is evident that the portion of the sweatband 13 which lines the inner surface of the front part 10 serves to slightly space the latter from the wearer's head.

The rear part 11 consists of a strip 15 which is pivotally secured at one end to the front part 10, and which strip underlies and engages a second strip 16 that is also secured to the front part 10. This outer strip 16 is formed with a slot 17, while the strip 15 carries a headed screw 18 the threaded stem of which extends through the slot 17. The screw 18, adjacent its head, is formed with a noncircular portion that is snugly received in a complementally shaped opening in the strip 15 (see Figure 5) to hold the screw 18 against rotation.

A retaining sleeve for maintaining the strips 15 and 16 in properly aligned relationship is shown at 19 and comprises a strip of material having the ends thereof overlapping and formed with aligned openings 20 through which the threaded stem of the screw 18 passes. A washer 21 is also carried by the screw stem 18 and engages the outer end portion of the sleeve 19. A wing nut 22 is screwed on the screw 18, and when tightened serves to maintain the strips 15 and 16 in an adjusted position. However, this nut 22 may be loosened to permit of adjustment in an obvious manner. When the wing nut 22 is to be operated the screw 18 is held against rotation by the reception of the noncircular portion adjacent to its head in the opening in the strip 15.

At this point it is well to note that the rear headband part may include any other known arrangement for providing adjustment as to the extent thereof, the particular arrangement illustrated being intended as no limitation on the invention.

One pivotal connection between the extremities of the strips 15 and 16 and the front part 10 is depicted in Figure 4 and is shown as comprising a pivot pin 23 which is headed on its inner end, as shown at 24, the head engaging the inner face of the front part 10. It is to be remembered that the front part 10 carries the sweatband 13; thus the head 24 in no way takes away from the snugness of the fit of the headband on the worker's head.

The pivot pin 23 extends through aligned openings in the front part 10 and the respective strip of the rear part 11, and at its outer end passes through an opening in a shield carrying strip 25. Between the strip 25 and the rear part 11 there is interposed a friction device, which may take any known form, but which preferably consists of a central washer 26 of a good friction material, and on each side of which are disposed metallic washers 27.

On the outer face of the strip 25 the pin 23 may also carry another metallic washer 28, and the end of this pivot pin may be peened over, as shown at 29, to maintain the assembled relationship of the various parts carried thereby. To the end of facilitating this peening over of the end of the pin 23, the latter is preferably of a hollow construction.

The shield carrying strip 25 is of a curved formation and is disposed in spaced relationship in front of the front headband part 10. This strip 25 may have integrally formed therewith an upwardly extending portion 30 that, it is noted, is spaced from the head cover 12.

As is clearly brought out in Figure 3, one part 70 of a snap fastening element is secured to the strip 25, as is shown at 31. The complementary part of this snap fastening element is carried by the upper edge of a shield 32 and is designated 33. It is to be understood that as many of

the snap fastening elements 31 and 33 as are required will be included on the shield carrying strip 25 and shield 32.

The shield 32 is made from a transparent material that is flexible so that it may be bent into the curved formation illustrated. The flexible transparent material should also have noninflammable qualities. Suitable cellulose acetate compounds have been proven to possess the required properties, and such materials are now available to the public.

The shield 32 is lined on each side and at the bottom by a metallic framework designated 34, which framework serves to impart rigidity to the shield 32 and causes the same to maintain the curved formation illustrated.

The framework 34 may take the U-shaped cross section illustrated in Figure 3, and may be secured to the shield 32 by punching depressions 20 on the inner face of the framework part 34, as shown at 35. The formation of these depressions 35 cause corresponding projections between the flanges defining the frame, and which projections engage and slightly bite into the shield 32 to maintain the assembled relationship.

With the protective device positioned in the manner shown in Figure 1 it is notable that the shield 32 is maintained in spaced relationship from the front face of the wearer, and the shield 30 carrying strip 25, together with the upwardly extending portion 30, is spaced from the front headband part 10 and the cover 12. Thus ventilation on the inner side of the shield is assured to prevent clouding of the shield, which ordinarily 35 might be caused by exhalation from the wearer's nose.

The shield 32 is maintained in the position illustrated due to the friction devices 26 and 27. However, the effect of these friction devices may 40 be readily overcome and the shield swung up into the out-of-the-way position depicted by the broken line showing of Figure 1. If under conditions of usage the shield 32 should become damaged, it may be readily replaced, due to the 45 detachable connection at 31—33 with the carrying strip 25.

It is also important to note that with the pivotal connection between the headband parts 10 and 11, and with the extent of the rear part 11 ad-

justable, the headband may be adjusted to fit the head of any particular wearer. Thus the rear part 11 may assume an angular position with respect to the front part 10, as shown by the broken lines of Figure 1.

While a preferred specific embodiment of the invention is hereinbefore set forth it is to be clearly understood that the invention is not to be limited to the exact constructions illustrated and described, because various modifications of these details may be provided in putting the invention into practice within the purview of the appended claims.

I claim:

1. A protective device of the character described comprising a headband, said headband consisting of two parts pivotally connected together, and a shield pivotally mounted on the pivotal connection between said headband parts.

2. A protective device of the character described comprising a headband, said headband consisting of two parts pivotally connected together, a shield pivotally mounted on the pivotal connection between said headband parts, and friction devices associated with the pivotal mountings for maintaining said shield in an adjusted position.

3. A headband for protective devices comprising a band having overlapping ends, one of said ends having a slot therein, a bolt having a head, a portion extending through said slot, means for preventing rotation of said bolt, a flat tubular casing encircling said ends and said bolt head and formed with an opening through which said bolt passes, and means on said bolt for clamping said ends 35 in desired relation to each other.

4. A headband for protective devices comprising a band having overlapping ends, one of said ends having a slot therein, a casing encircling said overlapping ends about said slotted end and 40 having overlapping extremities formed with openings aligned with each other and with said slot, a headed bolt extending through said aligned slot and openings with the head of the bolt within said casing, means for preventing rotation of said 45 bolt, and means disposed exteriorly of said casing and cooperating with the bolt for clamping said ends in desired relation to each other.

CHARLES EVANS BOWERS.
